UNITED STATES PATENT OFFICE.

CHAUNCEY D. FRENCH AND LOTT D. BROWN, OF DALLAS, OREGON.

AUTOMATIC CARRIAGE-REVERSING MECHANISM FOR TYPEWRITERS.

Application filed November 24, 1924. Serial No. 751,916.

To all whom it may concern:

Be it known that we, CHAUNCEY D. FRENCH and LOTT D. BROWN, citizens of the United States, residing at Dallas, in the county of Polk and State of Oregon, have invented certain new and useful Improvements in Automatic Carriage-Reversing Mechanisms for Typewriters, of which the following is a specification.

10 This invention relates to the art of typewriters, and has more particular reference to an automatic means for reversing the movement of the carriages thereof, the primary object of the invention residing in 15 the provision of a device of this character that may be readily associated with practically all forms of typewriters, for allowing the carriages to be automatically moved in a reverse direction, at any time required, 20 for obviously overcoming the necessity of the typist reversing the carriage by hand.

An additional object is to provide means 25 of this character that includes a rack bar rigidly connected with the appropriate end of the typewriter carriage, the teeth of which rack bar are in mesh with a small gear wheel upon one end of the armature shaft of an electric motor, which is supported at the same side of the typewriter, 30 which motor is in normally open circuit with a suitable source of energy, through the medium of a switch mechanism to be controlled by a button located at a convenient point at the typewriter key board, 35 for thereby overcoming the necessity of the operator removing his or her hand from the keyboard in the reversing of the carriage.

A further and important object is to provide a mechanism for automatically reversing the movement of the typewriter carriage, that may be associated with practically all forms of typewriters, in a quick and inexpensive manner, and one wherein the parts are not liable to readily become 45 out of order, and wherein the same may be repaired, whenever the occasion arises, by the operator, due to the extreme simplicity of the mechanism.

With the foregoing and other objects in view, as the nature of the invention will be better understood, the same comprises the novel form, combination, and arrangement of parts hereinafter more fully described, shown in the accompanying drawing and 55 claimed.

In the drawing, wherein like reference characters indicate corresponding parts throughout all of the views:

Figure 1 is a fragmentary front elevational view of a well known form of typewriter, equipped with our automatic carriage reversing mechanism, and

Figure 2 is a top plan view of certain of the mechanism for disclosing more clearly means for imparting the necessary rotation to the platen at the operation of the carriage.

Figure 3 is an elevation of this means, and

Figure 4 is a diagrammatic view disclosing the electric circuit of the mechanism.

Now, having particular reference to the drawing, there is shown a conventional form of typewriter that embodies the usual frame 5 and carriage 6, consisting of the usual 75 platen 7, paper guide 8, and other well known parts, not necessary of description.

Our invention, per se, constitutes the provision of a bracket shaped platform 9, that is rigidly secured to the appropriate side 80 of the frame 5 at a point slightly beneath the platen 7, and upon which is to be supported a small electric motor 10, of relatively low voltage, the forward end of the armature shaft of which is provided with a 85 relatively small spur gear 11, that is formed centrally upon its outer side with a small knob 12 for effecting a brake drum, for a purpose presently to be described.

Also supported upon said bracket shaped 90 platform 9 and between said motor 10 and typewriter frame 5, is an electric switch base 13, of fibre or other suitable non-conducting material. This switch base 13 carries, adjacent its upper edge a contact point 95 14, while at the lower edge thereof is an insulating block 15, to which is secured one end of a horizontally disposed strip of spring metal 16, which is so bent as to provide a pair of notches 17 and 18, intermediate the ends thereof.

Pivoted, as at 19, to the outer face of said switch rod 13, intermediate the contact 14 and spring strip 16 is a switch lever 20, of general T-shape, the lower arm of which is adapted to be selectively engaged in either of the notches 17 and 18 of the spring strip, for maintaining the upper arm in or out of engagement with the contact 14. The lateral arm 21 of said switch lever 110

has pivotal connection as at 22, with the upper end of a pendant link bar 23 that is, in turn, pivoted at its lower end to a horizontal rock bar 24, that is pivoted intermediate its ends as at 25, to the bracket platform 9, that supports the motor and switch before described. The inner end of this rock bar has pivotal connection to a downwardly extending relatively elongated link bar 26 that is guided through a bracket 27 on the adjacent side of the typewriter frame that is provided at its lower end with a button 28, that may be depressed by one of the fingers of the typewriter operator. The depression of this button obviously moves the switch lever upon its pivot as to engage the upper end thereof with the contact 14 of the switch.

Rigidly secured, in a manner to be presently described to the end of the typewriter 6 adjacent the motor and switch construction is a horizontal rack bar 29 formed upon its lower edge with rack teeth 30, that have mesh with the teeth of the spur gear 11 carried by the armature shaft of said motor 10. Secured to said rack bar 29, adjacent the opposite ends thereof, are pendant brackets 31-31 that carry at their lower ends rollers 32-32 which are adapted to engage, at the limit of movement of the carriage 6, in opposite directions, the switch lever 20, for obviously throwing the same into or out of engagement with the contact 14 of the switch mechanism.

Included in our reversing means for typewriter carriages is a storage battery 33 of suitable voltage that may be disposed alongside the typewriter frame. One pole of this battery is electrically connected as at *a* with the switch lever 20, the other pole thereof being electrically connected as at *b* with one contact of the motor 10, the other contact of said motor being electrically connected as at *c* with the contact 14 of the switch mechanism.

From the foregoing description, when considered in conjunction with the accompanying drawing, it will at once be apparent that the normal position of the switch lever 20 is out engagement with the contact 14. The carriage 6, moving in a direction toward the left during the operation of the machine, will naturally move the rack bar 29 in a similar direction, and as the same is reaching its limit of movement, the roller 32, at the right hand end of the bar will strike the switch lever, for moving the same into engagement with the contact 14, immediately completing the circuit between the storage battery and motor, and a rotation of the same will return the carriage to its position at the right of the typewriter. Immediately upon reaching a limit of movement in a right hand direction, the other roller 32 will engage the switch lever 20

for moving the same out of contact with the member 14, whereupon the circuit will be broken from the battery to the motor.

Also carried by the rack bar 29 adjacent the inner end thereof is a pendant spring strip 34 that engages the before mentioned brake drum knob 12 of the spur gear 11 for stopping the rotation of the armature shaft of the motor, immediately upon the breaking of the circuit to the motor from the storage battery.

As a means for securing the rack bar to the carriage of the typewriter, there is provided a bar 35 at the end of the platen, the same being secured at its inner end, in any manner desirable to the carriage. Secured to this bar is a lateral bracket 36 that is formed at its front end with a horizontal extension 37 through which extends a stub shaft 38, that also projects through the adjacent end of the rack bar 29, which is in spaced relation to said extension 37. This end of the rack bar is integrally joined to the bracket 36 by a connecting bar 39.

In the use of our device, it is necessary that the thumb wheel upon the right hand end of the platen be removed, and a bevel gear 40 substituted therefor. In mesh with this bevel gear is a similar gear 41, upon the front end of the stub shaft 38. Said shaft 38 carries intermediate the rack bar 29 and horizontal extension 37, a ratchet or spur gear 42.

Longitudinally slid able in bearings 43, upon the rear side of the rack bar is a two part rod 44, the sections of which may be adjustably secured together, through the medium of means designated 45, the same permitting the rod to be increased or diminished in length for a purpose presently to be described.

Journalized in the rack bar 29 is a shaft 46, that is equipped at its outer end with a gear 47, the teeth of which will engage the teeth of the motor shaft gear 11. It will be necessary that the thickness of the gear 11, be such as to engage the teeth of the rack bar 29, and the teeth of the gear 47.

The inner end of the shaft 46 is equipped with a cam wheel 48, in close relation with which is the adjacent end of the bar 44, normally maintained in this relation through the medium of the expasible springs 49-49. One of the springs 49 is disposed between a bearing 50 and an abutment on the rod, and the other spring 49 is disposed between a bearing 56 and the connecting means 45.

In the operation of our mechanism, a depression of the button will close the circuit to the motor and a rotation thereof will operate the rack bar to move the carriage in a direction toward the right. As the rack bar is moving toward the right, the gear wheel 47 will encounter the gear 11 of the

motor shaft for operating the cam wheel 48. The rotation of this cam wheel will force the rod in a direction toward the left against the action of the springs, which rod will engage the gear 42 for rotating the shaft 38 and consequently the platen 8.

The length of the rod 44 will regulate the rotation of the platen for single, double, or triple line spacing.

10 From the foregoing description, when considered in conjunction with the accompanying drawing, it will be readily seen that we have provided a highly novel, simple, and inexpensive form of automatic carriage reversing and platen rotating mechanism for typewriters, and one that will meet with all of the requirements for a successful commercial use.

Having thus described our invention, 20 what we claim as new and desire to secure by Letters Patent is:

1. An automatic carriage reversing mechanism for typewriters comprising a bracket supported upon one side of the typewriter frame, a motor supported on the bracket, the armature shaft of said motor being equipped with a gear wheel, a rack bar secured to the adjacent end of the carriage and disposed to one side thereof and having its teeth in mesh with the teeth of the gear wheel, a switch in circuit with the motor, abutments, one adjacent each end of the rack bar for engaging the switch for making and breaking the motor circuit, and a spring mounted on the rack bar for engaging the armature shaft of the motor for braking the same after the switch has been moved to an off position.

2. In an automatic carriage reversing mechanism for typewriters, a motor supported upon one side of the typewriter frame, the armature shaft of said motor being equipped with a gear wheel, a horizontal rack bar secured to the adjacent end of the carriage to one side of the platen thereof, a gear operatively associated with the platen, a second gear rotatably mounted on the rack bar, and in mesh with the gear operatively associated with the platen, a third gear operatively associated with the second gear, a rod slidably mounted on the rack bar having one end engageable with

the third gear, a cam rotatably mounted on the rack bar and associated with the other end of the rod, and a gear operatively associated with the cam for meshing with the gear on the armature of the motor.

3. In an automatic carriage reversing mechanism for typewriters, a motor supported upon one side of the typewriter frame, the armature shaft of said motor being equipped with a gear wheel, a horizontal rack bar secured to the adjacent end of the carriage to one side of the platen thereof, a gear operatively associated with the platen, a second gear rotatably mounted on the rack bar, and in mesh with the gear operatively associated with the platen, a third gear operatively associated with the second gear, a rod slidably mounted on the rack bar having one end engageable with the third gear, a cam rotatably mounted on the rack bar and associated with the other end of the rod, and a gear operatively associated with the cam for meshing with the gear on the armature of the motor.

4. In an automatic carriage reversing mechanism for typewriters, a motor supported upon one side of the typewriter frame, the armature shaft of said motor being equipped with a gear wheel, a horizontal rack bar secured to the adjacent end of the carriage to one side of the platen thereof, a gear operatively associated with the platen, a second gear rotatably mounted on the rack bar, and in mesh with the gear operatively associated with the platen, a third gear operatively associated with the second gear, a rod slidably mounted on the rack bar having one end engageable with the third gear, a cam rotatably mounted on the rack bar and associated with the other end of the rod, and a gear operatively associated with the cam for meshing with the gear on the armature of the motor, means for adjusting the length of the rod.

In testimony whereof we affix our signatures.
